UNITED STATES PATENT OFFICE

2,383,422

CHEMICAL FEEDING PUMP

John F. Singleton, Van, Tex.

Application February 23, 1944, Serial No. 523,584

1 Claim. (Cl. 103—153)

This invention relates to a novel ways and means, characterized essentially by an automatically functioning chemical pump, for forcing chemicals or other liquids into pressure or non-pressure pipe-lines, tanks and analogous receiving containers. Briefly, the structural arrangement adopted for my purposes is characterized by a single double-action pump cylinder and piston unit which operates on both the up and down strokes of the piston and is, therefore, devised so that the pressure internally is equalized and so that by subjecting the piston rod to the action of a weight applicable thereto, the piston will force the chemical or other liquid into the pressure line or other container at the desired proportionate rate.

More specifically, the overall structure is characterized by the aforementioned single type double-acting pump means or unit, this having valved connection at one point with a chemical supply reservoir or tank, having valved pipe connection at another point with the main fluid conducting conduit or pipe-line, and there being a third valved auxiliary pipe-line from the conduit to the top of the pump cylinder to achieve the desired equalizing of the fluid in said pump cylinder on opposite sides of the piston head.

Other features and advantages will become more readily apparent from the following description and the accompanying illustrative drawings.

In the drawings, wherein like numerals are employed to designate like parts or elements throughout the same:

Figure 1 is an elevational view of the complete assemblage, that is, the chemical supply reservoir or tank, main conduit, double-acting pump and valved piping connections between the respective parts.

Figure 2 is an enlarged vertical section on the plane of the line 2—2 of Figure 1.

Figure 3 is a horizontal section on the line 3—3 of Figure 2.

Figure 4 is a fragmentary detail view showing the removable lead ball weight on the upper end of the piston rod.

Referring now to the drawings by distinguishing reference numerals, the numeral 5 designates an appropriate stationary support which may include a platform. Running horizontally beneath this is the main pressure line or conduit 6. Supported on the platform at the left is the chemical containing and supply tank or reservoir 7. The single double-acting pump is indicated at 8. Considering specifically the con-

struction of the pump 8, attention is directed to Figure 2. It comprises a cylinder 9 secured to a base plate 10 which is bolted or otherwise secured to the platform. This is provided with inlet and discharge ports 11 and 12 properly proportioned and threaded. At the top is an annular collar 13 forming a ledge for securing the disk-like top plate 14 in place. The plate 14 is bolted to the flange 13 as at 15 and is provided with a screw-threaded port 16. The plate also carries an appropriate stuffing box or gland 17 for the reciprocating piston rod 18. The head of the piston 19 is provided with upper and lower packing cups 20 and 21, these being in frictional fluid-tight contact with the inner surface of the cylinder. As brought out in Figure 1 the intermediate part of the piston rod is shouldered as at 22 and forms a reduced extension 23 to accommodate a ball, that is, a lead weight 24 of ball or other form. In practice, it is possible to use a series of washer-like or disk weights which can be stacked on the shoulder 22 and held in place by the reduced stem 23.

A chemical delivery pipe-line 25 is connected with the bottom of the chemical tank 7 and is, in turn, connected with the threaded hole 11 in the bottom of the pump cylinder. This is provided with a cut-off valve 26 of appropriate construction. An auxiliary feeder pipe-line 27 connects with the other hole 12 and is, in turn, connected at its opposite end, as at 28 with the main conduit or pressure pipe-line 6. Here again we have a hand-regulated valve 29 of appropriate construction in the pipe-line 27. At a longitudinally spaced point there is an equalizing auxiliary pipe-line 30 which has its upper delivery end attached to the top of the pump cylinder above the piston as at the point 16. Close to the pump is a drain-cock 31. The numeral 32 designates a cut-off valve.

The operation is as follows: With the piston or plunger down in the pump cylinder, the valve 29 in the feeder line 27, and the valve 32 in the equalizing pipe-line 30 are both closed. The valve 26 in the line 25 is then opened to permit flow of chemical from the supply tank 7 to the pump cylinder 9. The pump piston is raised by hand and the cylinder of the pump filled with the chemical. The valve 26 is then closed and the two valves in the auxiliary pipe-lines, that is, the valves 26 and 32 are then opened to equalize the pressure above and below the piston, that is, in the upper and lower chambers above and below the piston in the cylinder 9. The metal ball or weight 24 is then placed in position on the up-

per end of the piston rod and this is of sufficient weight to overcome the friction of the piston head and packing cups on the wall of the cylinder. The valve 29 is then adjusted to regulate the flow of the fluid, that is, the chemical into the pressure line and the unit is in operation for continued automatic operation. The pipe-line 30 from the pressure line to the upper intake of the pump cylinder, through valve 32, connects to the rear on the main pressure line sufficiently distant so that the supply line from the pump to the pressure line carries the chemical into the pressure line and on with the flow of the fluid being treated. To refill, the valves are set again as above noted and the drain-cock 31 is opened to permit the untreated fluid in the top chamber to drain out as said pump cylinder is refilled. The drain-cock is then closed and the operation is repeated.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed as new is:

In a structure of the class described, a pumping cylinder for delivering fluid under pressure, said cylinder embodying a base with an outstanding marginal flange adapted for anchorage on a relatively fixed support, the bottom of said cylinder having a chemical intake and supply port, a valved chemical supply pipe connected to said port and adapted for connection with a chemical supply tank, said bottom being further provided with a chemical discharge port, a valved pipe connected to said chemical discharge port, the major portion of said cylinder being imperforate, 5 a closing plate for the top of the cylinder having a stuffing box and a port, a third valved pipe, this connected with the last-named port, a piston comprising a head slidable in said cylinder and including upper and lower packing cups, said head serving to divide the cylinder into upper and lower chambers in respect to said top and bottom ports, said piston also including a reciprocatory rod extending upwardly through and beyond said stuffing box, and a detachable ball 10 15 20 25 weight having a socket mounted on the upper end of said piston rod.

JOHN F. SINGLETON.
